11 Claims. (Cl. 178—7.2)

1

This invention relates to television picture signal generating tubes, and more particularly relates to image dissector tubes of the type where the picture signal is amplified by dynamic electron multiplication.

An image dissector tube as used conventionally comprises a photosensitive cathode on which an optical image is focused for converting it into an electron cloud representative of the optical image. A shield provided with a minute scanning aperture is spaced from the photosensitive cathode. The electron cloud is cyclically deflected across the scanning aperture so that at any instant electrons from a selected elemental area of the photocathode are able to enter the aperture. It is conventional practice to multiply the electrons passing through the scanning aperture by means of an electron multiplier.

It has been suggested to multiply the electrons which have passed through the scanning aperture of an image dissector tube by dynamic electron multiplication. To this end the electrons are oscillated repeatedly between two spaced secondary electron emissive surfaces so that secondary electrons are liberated at a ratio greater than unity each time a primary electron impacts one of the electrodes. A dynamic electron multiplier of this type is commonly referred to as a multipactor and may be arranged to be self-oscillating. When the electrons which are multiplied in the multipactor are allowed to oscillate continuously between the secondary electron emissive surfaces, a saturation current will finally be obtained so that the electron stream in the multipactor is no longer representative of the light characteristics of a selected area of the photocathode. Therefore, it is necessary to interrupt the oscillation of the electrons in the multipactor periodically by some means such as a high frequency oscillation generator. When a multipactor is periodically interrupted in this manner, it tends to be unstable unless it is driven by waves at a suitable frequency impressed from an extraneous source on the secondary electron emissive surfaces. Furthermore, a special oscillation generator or some other means must be provided for periodically interrupting the dynamic multiplication of the selected electrons.

It is an object of the present invention, therefore, to provide an image dissector tube where the picture signals developed by the dissector are multiplied by dynamic electron multiplication, without the necessity of periodically interrupting the electron multiplication.

A further object of the invention is to provide

2

a picture signal generating tube of the image dissector type where only electrons from successive elemental areas of a photocathode are continuously oscillated between spaced secondary electron emissive surfaces for multiplying the selected electrons by dynamic electron multiplication.

In accordance with the present invention, there is provided a television picture signal generating tube comprising a photosensitive cathode arranged for converting an optical image into an electron cloud representative of the optical image. A secondary electron emissive surface is provided which is spaced from the cathode and has an area that is small in comparison with the area of the cathode. Electron deflecting means are provided for cyclically sweeping the electron cloud across the secondary electron emissive surface. There is also provided means for continuously oscillating electrons emitted from successive elemental areas of the cathode between the secondary electron emissive surface and the cathode, so that electrons from each selected area impact the secondary electron emissive surface a predetermined number of times. A target is provided for collecting the amplified electron stream which has been swept across the secondary electron emissive surface. Thus, an amplified train of picture signals is derived which is representative at any instant of the light characteristics of a selected elemental area of the optical image.

For a better understanding of the invention, together with other and further objects thereof, reference is made to the following description, taken in connection with the accompanying drawings, and its scope will be pointed out in the appended claims.

In the accompanying drawings:

Fig. 1 is a schematic representation of an image dissector tube and associated electric circuits embodying the present invention;

Fig. 2 is a front elevational, fragmentary view taken on line 2—2 of Fig. 1 and illustrating a portion of an electrode of the image dissector tube having an aperture therein and an adjacent secondary electron emissive surface;

Fig. 3 is a schematic side view of the photosensitive cathode and a spaced electrode of the image dissector tube of Fig. 1 illustrating repeated traversals of selected electrons between the two electrodes;

Fig. 4 is a front elevational view similar to Fig. 2 of a modification of the apertured electrode with an associated secondary electron emissive wire arranged adjacent the aperture;

Fig. 5 is a sectional view taken on line 5—5 of Fig. 4; and

Fig. 6 is a schematic representation of a modification of the image dissector tube of the invention and associated electric circuits.

Referring now more particularly to Fig. 1 of the drawings, there is illustrated image dissector tube 1 comprising an evacuated envelope 2 formed with optical window 3. Translucent photosensitive cathode 4 is arranged in envelope 2 adjacent optical window 3. Electrode 5 is arranged opposite photosensitive cathode 4 in envelope 2. Anode 6, which preferably is ring-shaped as shown, is arranged midway between photosensitive cathode 4 and electrode 5 so as not to interfere with the normal path of an electron cloud moving from cathode 4 toward electrode 5.

Photosensitive cathode 4 is arranged for converting an optical image projected thereon into an electron cloud. For the purpose of projecting an optical image of an object schematically represented at 6' through window 3 upon photosensitive cathode 4, there is provided lens system 7. Photosensitive cathode 4 preferably is also made secondary electron emissive in a manner well known in the art. It may be pointed out that most photosensitive materials are also good secondary electron emitters.

Electrode 5 is provided with aperture 8. Surface 10, which may be formed on electrode 5, is made secondary electron emissive and is arranged adjacent aperture 8, as illustrated particularly in Fig. 2. The area of surface 10 is small in comparison with the area of photosensitive cathode 4. In order to deflect the electron cloud developed by photosensitive cathode 4 in two directions normal to each other, there are provided line scanning wave generator 11 and field scanning wave generator 12 arranged for developing sawtooth deflecting currents at the line scanning frequency and field scanning frequency, respectively. Scanning wave generators 11 and 12 are connected, respectively, with scanning coils 13 and 14 all of conventional construction.

Focusing coil 15 energized by a suitable current source such, for example, as battery 16 is arranged for providing a magnetic field to focus electrons forming an electron cloud secondary electron emissive surface 15 as well as on photosensitive cathode 4. An antiresonant circuit 20, including variable condenser 21 and inductor 22, is connected in parallel between photosensitive cathode 4 and electrode 5. The mid point of inductor 22 is connected by a center tap through blocking condenser 23 to anode 6. Ground is connected to the center tap of inductor 22 as illustrated. A voltage source such, for example, as battery 24 is connected across potentiometer 25 and has its negative terminal grounded as shown. Positive potential is supplied to anode 6 through a suitable tap on potentiometer 25 connected between anode 6 and condenser 23. This potential may be of the order of magnitude of 500 volts. Oscillation generator 26 is arranged for developing a sinusoidal voltage wave output which is connected across inductor 27 inductively coupled to inductor 22.

Image dissector tube 1 operates as follows. Light from object 6', which is focused on photosensitive cathode 4 by optical system 7, liberates photoelectrons therefrom which form an electron cloud. The photoelectrons are attracted by the positive potential applied to anode 6 through battery 24. The magnetic focusing field devel-

oped by focusing coil 15 guides the photoelectrons toward electrode 5. At the same time the magnetic deflecting field developed by the sawtooth currents flowing through deflecting coils 13 and 14 sweeps the photoelectrons across secondary electron emissive surface 10 and aperture 8 in two directions normal to each other. Secondary electron emissive surface 10 should be arranged so that the photoelectrons are first swept across surface 10 and then into aperture 8, that is, the line scanning field should direct the electrons from surface 10 into aperture 8.

The photoelectrons liberated from cathode 4 are accelerated by the positive potential applied to anode 6 until they reach the median plane of anode 6 whereafter they are decelerated again so that they reach electrode 5 with substantially zero velocity. However, it should be pointed out that the photoelectrons will impact electrode 5 with a small velocity, corresponding to their initial velocity which depends upon the wave length of the light focused on photosensitive cathode 4 and upon the work function of the photosensitive material of cathode 4. The initial velocity of the electrons, however, is normally insufficient to impart enough energy to the electrons to liberate secondary electrons from surface 10.

Oscillation generator 26 impresses a high frequency sinusoidal voltage wave upon inductor 22. The half period of the frequency of the voltage wave developed by oscillator generator 26 should approximately equal the transit time of an electron between cathode 4 and electrode 5. At a certain interval within each cycle of the wave developed by oscillation generator 26 a photoelectron liberated from cathode 4 will be accelerated toward electrode 5. The accelerated electron should impact surface 10 with sufficient energy to release secondary electrons at a ratio greater than unity.

Due to the deflecting field developed by the sawtooth currents flowing through deflecting coils 13 and 14, electrons from successive elemental areas of cathode 4 will be directed toward secondary electron emissive surface 10. The electrons from all but the selected areas are collected by electrode 5. Accordingly, electrode 5 with the exception of surface 10 should be made of a material which is not secondary electron emissive such as carbon. In some cases it may be sufficient if electrode 5 is not treated with a secondary electron emissive material to insure that the ratio of primary electrons impacting electrode 5 to secondary electrons is less than unity.

The secondary electrons liberated from surface 10 by primary electrons from a selected elemental area of cathode 4 are again attracted by the positive potential of anode 6. Before or at the time the electrons have reached the median plane of anode 6 the alternating potentials on cathode 4 and electrode 5 have reversed so that the electrons are now attracted by cathode 4 which they will impact with sufficient energy to liberate secondary electrons at a ratio greater than unity. In this manner the electrons from a selected elemental area of cathode 4 are impacted repeatedly between surface 10 and cathode 4. This continues until the deflecting field developed by the sawtooth currents flowing through deflecting coils 13 and 14 has swept the multiplied electron stream across surface 10 and into aperture 8. The electrons from the selected areas are thus multiplied by dynamic electron multiplication.

The number of impacts which the electrons from a selected elemental area of cathode 4 will carry out depends upon a number of factors, such as the size of surface 10, the speed with which the electrons are swept across surface 10 and the electron transit time between cathode 4 and electrode 5. Preferably, the electrons from a selected cathode area make five traversals between cathode 4 and surface 10 before they are deflected into aperture 8.

The transit time of the electrons preferably should be so short that these five traversals take place during the time one picture element is scanned. It may be assumed, for example, that 30 complete pictures or frames are scanned in one second and that each picture consists of 700 lines. Each line will accordingly consist of 700 picture elements, and, therefore, $700^2 \times 30$ or about 15,000,000 picture elements are scanned per second corresponding to a frequency of 15 megacycles per second. Since the electrons are required to make five traversals during the time interval one picture element is scanned, the frequency developed by oscillation generator 26 should be about 75 megacycles per second with the above assumptions.

Referring now to Fig. 3, there is illustrated the path 30 along which an electron from a selected elemental area 31 travels between cathode 4 and secondary electron emissive surface 10 before it is deflected into aperture 8. It will be understood that the electron path has been shown schematically only. The alternating accelerating potentials applied to cathode 4 and electrode 5 as well as the distance between the two electrodes should be such that the electrons travel from cathode 4 to surface 10 and back again in the required time. It will be appreciated that the velocity of the electrons is also dependent to some extent on the magnetic focusing field developed by coil 15. As shown in Fig. 3, the electron impacts surface 10 as well as cathode 4 twice and, accordingly, the multiplied electron stream deflected through aperture 8 is equivalent to that obtained by a four stage static electron multiplier.

It should be pointed out that at the time the amplified electron current, representative of cathode area 31, travels through aperture 8, some electrons from adjacent cathode areas will also be deflected into aperture 8. Some of these electrons have been liberated from cathode area 32 and have made three traversals between cathode 4 and surface 10 before they reach aperture 8. At the same time some electrons will reach aperture 8 which have been liberated from cathode area 33 and which have traversed the space between cathode 4 and electrode 5 once only.

It may be assumed that each primary electron liberates five secondary electrons from either surface 10 or cathode 4. The electron current represented by those photoelectrons which have been liberated from area 33 may be assumed to be unity. The electrons which originated from area 32 have impacted surface 10 and cathode 4 twice, and, therefore, this multiplied electron current passing through aperture 8 is equivalent to 5² or 25. On the other hand, the electrons which have originated from area 31 have impacted surface 10 and cathode 4 four times, and thus the multiplied electron current from area 31 is 5⁴ or 625. Hence, the current of the multiplied electrons from area 32 is 4% of the current represented by the multiplied

electron stream originating from area 31. The electron current of the photoelectrons liberated from area 33 is 1.6% of that of the electrons liberated from area 31. These three electron currents will be superimposed to constitute the output signal. However, it will be evident that blurring of the reproduced image due to the picture signals containing components from adjacent cathode areas will be negligible.

10. The multiplied electron stream passing through aperture 8 is represented at any instant of the light characteristics of a selected cathode area. This electron stream may be further multiplied by static electron multiplier 35 comprising a plurality of multiplier stages 36 and electron collector 37. The first multiplier stage 36 is kept at a potential that is positive with respect to electrode 5 by means of a suitable tap connected to potentiometer 25. The succeeding multiplier stages 36 are maintained at increasingly positive potentials by means of taps connected to potentiometer 25. Electron collector 37 is kept at a potential that is positive with respect to the last multiplier stage 36 and is connected through load resistor 40 to the positive pole of battery 24. Bypass condenser 41 connected between ground and the positive pole of battery 24 is arranged to provide a low impedance path for alternating current. The amplified output signal is developed across resistor 40 and may be coupled through condenser 42 to a television preamplifier.

Referring now to Figs. 4 and 5, there is illustrated a modified electrode 45 corresponding to electrode 5 of Figs. 1 and 2. Electrode 45 is provided with aperture 46. Wire 47 extends across the surface of electrode 45 which faces photosensitive cathode 4. Wire 47 has a portion 48 arranged adjacent aperture 46 which is made secondary electron emissive. In some cases electrode 45 and wire 47 may be used with advantage in image dissector tube 1 illustrated in Fig. 1 instead of electrode 5 and secondary electron emissive surface 10.

Referring now to Fig. 6, in which like components are designated by the same reference numerals as were used in Fig. 1, there is illustrated image dissector tube 50 which is essentially identical to image dissector tube 1 illustrated in Fig. 1. However, instead of electrode 5, there is provided electrode 51 having an area that is small in comparison with that of photosensitive cathode 4. Electrode 51 is provided with aperture 52 and secondary electron emissive surface 53 arranged adjacent aperture 52. There is further provided collecting electrode 54 arranged to collect at any instant electrons from all but a selected area of photosensitive cathode 4. Collecting electrode 54 is provided with aperture 55 which may be larger than aperture 52 in electrode 51 to permit passage of the multiplied electron stream therethrough. Electron collector or target 56 is arranged behind apertures 52 and 55 for collecting the multiplied electron stream which has passed through apertures 52 and 55. It is to be understood that target 56 may also be arranged in the space occupied by aperture 52 and electrically insulated from electrode 51.

Electrode 51 is connected to antiresonant circuit 20 as is electrode 5 of image dissector tube 1. Collecting electrode 54 may be supplied with a potential that is positive against the average potential of cathode 4 and electrode 51 by means of a suitable tap on potentiometer 25. Target 56 may be kept at a still higher positive potential by connecting it to potentiometer 25 through load

resistor 40. The output signal is developed across load resistor 40 and may be coupled to a television preamplifier through coupling condenser 42. It is also feasible to provide a static electron multiplier, such as illustrated at 35 in Fig. 1, between electrode 51 and target 56.

Image dissector tube 50 operates in the same manner as image dissector tube 1. Electrons from successive selected elemental areas of cathode 4 are directed toward secondary electron emissive surface 53 where they liberate secondary electrons by impact. These electrons are repeatedly oscillated between surface 53 and cathode 4 before they are swept across aperture 52 and collected by target 56. It will be understood that the electrons from successive selected elemental areas of cathode 4 are oscillated continuously between surface 53 and cathode 4. It is not necessary, however, to interrupt the dynamic multiplication of the electrons because the selected electrons are deflected into aperture 52 after a predetermined number of impacts on surface 53 and cathode 4.

It is also feasible to dispense with oscillation generator 26 and inductor 27. In that case the image dissector tube of the invention as illustrated in Figs. 1 and 6 will operate in the manner of a multipactor and develop an alternating current oscillating in antiresonant circuit 20 at a frequency whose one-half period approximately equals the transit time of an electron between cathode 4 and surfaces 53 or 10, respectively. For example, the operation of the tube of Fig. 1 is as follows, but it is to be noted that the tube of Fig. 6 operates in similar fashion.

The photoelectrons liberated from photosensitive cathode 4 will leave the cathode positively charged, and, therefore, a current will flow from cathode 4 through the left hand portion of inductor 22 and its center tap to the negative terminal of battery 24. The current flowing from photosensitive cathode 4 to battery 24 develops a potential drop which appears on cathode 4 and electrode 5 in such phase as to accelerate the photoelectrons causing them to impact surface 10 with a finite velocity. Accordingly, secondary electrons will be liberated from surface 10 at a ratio greater than unity.

Now electrode 5 has acquired a negative charge deficiency due to its loss of electrons and, accordingly, a current will flow from electrode 5 through the right hand portion of inductor 22 and its center tap to the negative terminal of battery 24. This current will again cause a potential drop appearing on cathode 4 and electrode 5 in such a phase as to accelerate the secondary electrons toward photosensitive cathode 4. Then the cycle repeats again until the electrons from a selected area are passed through aperture 8. In that instant electrons from the next selected area of cathode 4 will be directed toward secondary electron emissive surface 10 so that the oscillation of the electrons continues without interruption.

A multipactor arranged as an oscillation generator is disclosed, for example, in the United States Patent No. 2,071,516 granted to Philo T. Farnsworth on February 23, 1937. The multipactor has been found to start oscillating when a photoelectric current is initiated in the tube.

While there has been described what is at present considered the preferred embodiment of the invention, it will be obvious to those skilled in the art that various changes and modifications may be made therein without departing from

the invention, and it is, therefore, aimed in the appended claims to cover all such changes and modifications as fall within the true spirit and scope of the invention.

5. What is claimed is:

1. A television picture signal generating tube comprising a photosensitive cathode arranged for converting an optical image into an electron cloud representative of said optical image, an electrode spaced from said cathode and having a secondary electron emissive surface, electron deflecting means for cyclically sweeping said electron cloud across said surface, means for continuously oscillating electrons emitted from successive elemental areas of said cathode between said surface and said cathode so that electrons from each of said elemental areas impact said surface a predetermined number of times and thereby produce an amplified electron stream, means cooperating with said deflecting means for sequentially selecting said amplified electron stream from said electron cloud, and a target arranged for collecting said selected electron streams thereby to derive an amplified train of picture signals representative at any instant of the light characteristics of an elemental area of said optical image.

2. A television picture signal generating tube comprising a photosensitive cathode arranged for converting an optical image into an electron cloud representative of said optical image, an electrode spaced from said cathode and having a secondary electron emissive surface covering an area that is small in comparison with the area of said cathode, electron deflecting means for cyclically sweeping said electron cloud simultaneously in two directions normal to each other across said surface, means for continuously oscillating electrons emitted from successive elemental areas of said cathode between said surface and said cathode so that electrons from each of said elemental areas impact said surface repeatedly and thereby produce an amplified electron stream, means embodied in said electrode and cooperating with said deflecting means for sequentially selecting said amplified electron streams from said electron cloud, and a target arranged for collecting said selected electron streams, thereby to derive an amplified train of picture signals representative at any instant of the light characteristics of an elemental area of said optical image.

3. A television picture signal generating tube comprising a photosensitive cathode arranged for converting an optical image into an electron cloud representative of said optical image, an electrode spaced from said cathode and having a secondary electron emissive surface covering an area that is small in comparison with the area of said cathode, electron deflecting means for cyclically sweeping said electron cloud simultaneously in two directions across said surface, means for continuously oscillating electrons emitted from successive elemental areas of said cathode between said surface and said cathode so that electrons from each of said elemental areas impact said surface a predetermined number of times and thereby produce an amplified electron stream, a collector for collecting all electrons except those forming said amplified electron stream, and a target arranged for collecting the amplified electron stream which has been swept across said surface, thereby to derive an amplified train of picture signals representative at any instant of the light characteristics of

a selected elemental area of said optical image.

4. A television picture signal generating tube comprising a photosensitive cathode arranged for converting an optical image into an electron cloud representative of said optical image, an electrode having an aperture therein and being spaced from said cathode, a secondary electron emissive surface formed on said electrode adjacent said aperture and having an area that is small in comparison with the area of said cathode, electron deflecting means for cyclically sweeping said electron cloud successively across said surface and said aperture, means for continuously oscillating electrons emitted from successive elemental areas of said cathode between said surface and said cathode so that electrons from each of said elemental areas impact said surface a predetermined number of times and thereby produce an amplified electron stream for passage through said aperture, and a target for collecting the amplified electron stream which has passed through said aperture, thereby to derive an amplified train of picture signals representative at any instant of the light characteristics of a selected elemental area of said optical image.

5. A television picture signal generating tube comprising a photosensitive cathode arranged for converting an optical image into an electron cloud representative of said optical image, an electrode having an aperture therein and being spaced from said cathode, a secondary electron emissive surface arranged adjacent said aperture and having an area that is small in comparison with the area of said cathode, electron deflecting means for cyclically sweeping said electron cloud simultaneously in two directions successively across said surface and said aperture, means for applying operating potentials to said cathode and said electrode to continuously oscillate electrons emitted from successive elemental areas of said cathode between said surface and said cathode so that electrons from each selected area impact said surface a predetermined number of times before they are swept thereacross to pass into said aperture, an electron multiplier arranged behind said aperture for further amplifying the electron stream which has passed through said aperture, and a target for collecting said amplified electron stream, thereby to derive an amplified train of picture signals representative at any instant of the light characteristics of a selected elemental area of said optical image.

6. A television picture signal generating tube comprising a photosensitive cathode arranged for converting an optical image into an electron cloud representative of said optical image, an electrode having an aperture therein and being spaced from said cathode, a secondary electron emissive surface arranged adjacent said aperture and having an area that is small in comparison with the area of said cathode, electron deflecting means for cyclically sweeping said electron cloud simultaneously in two directions normal to each other successively across said surface and said aperture, means for applying operating potentials to said cathode and said electrode to continuously oscillate electrons emitted from successive elemental areas of said cathode between said surface and said cathode so that electrons from each selected area impact alternately said surface and said cathode a predetermined number of times before they are swept thereacross to pass into said aperture, electron collecting means

for collecting electrons from all but said selected area, and a target for collecting the amplified electron stream which has passed through said aperture, thereby to derive an amplifier train of picture signals representative at any instant of the light characteristics of a selected elemental area of said optical image.

7. A television picture signal generating tube comprising a photosensitive cathode arranged for converting an optical image into an electron cloud representative of said optical image, an electrode having an aperture therein and being spaced from said cathode, a secondary electron emissive surface arranged adjacent said aperture and having an area that is small in comparison with the area of said cathode, electron deflecting means for cyclically sweeping said electron cloud simultaneously in two directions normal to each other successively across said surface and said aperture, means for applying operating potentials to said cathode and said electrode to continuously oscillate electrons emitted from successive elemental areas of said cathode between said surface and said cathode so that electrons from each selected area impact said surface a predetermined number of times before they are swept thereacross to pass into said aperture, electron collecting means for collecting electrons from all but said selected area, an electron multiplier arranged behind said aperture for further amplifying the electron stream which has passed through said aperture, and a target for collecting said amplified electron stream, thereby to derive an amplifier train of picture signals representative at any instant of the light characteristics of a selected elemental area of said optical image.

8. In a television image dissector tube having an evacuated envelope, a photosensitive cathode mounted in said envelope, an electrode in said envelope spaced from said cathode and provided with a scanning aperture, said electrode having a secondary electron emission ratio of less than unity, a secondary electron emissive surface formed on said electrode adjacent said aperture and facing said cathode, said surface having a secondary electron emission ratio of more than unity and also having an area that is small in comparison with the area of said cathode, and means for impressing an alternating voltage upon said cathode and said electrode.

9. In a television image dissector tube having an evacuated envelope, a photosensitive cathode mounted in said envelope, an electrode in said envelope spaced from said cathode and provided with a scanning aperture, said electrode also having a secondary electron emission ratio of less than unity, a linear member extending across the surface of said electrode facing said cathode comprising a portion adjacent said aperture having a secondary electron emission ratio of more than unity, and means including a source of alternating current coupled to said cathode and to said electrode for producing an oscillating field between said cathode and said electrode.

10. In a television image dissector tube having an evacuated envelope, a photosensitive cathode mounted at one end of said envelope, an electron collecting electrode having an aperture mounted at the opposite end of said envelope, said collecting electrode having a secondary electron emission ratio of less than unity, a second electrode mounted adjacent said collecting electrode and having a scanning aperture in alignment with said collecting electrode aperture, a secondary

electron emissive surface formed on said second electrode adjacent said scanning aperture and facing said cathode, said surface having an area that is small in comparison with the area of said cathode and having a secondary electron emission ratio of more than unity, the remaining surface of said second electrode having a secondary electron emission ratio of less than unity, and means including a source of oscillations coupled to said cathode and to said second electrode for producing an oscillating field between said cathode and said second electrode.

11. In a television image dissector tube having an evacuated envelope, a photosensitive cathode mounted at one end of said envelope, an electron collecting electrode having a relatively large aperture mounted at the opposite end of said envelope, said collecting electrode having a secondary electron emission ratio of less than unity, a second electrode mounted on the cathode side of said collecting electrode in alignment with said relatively large aperture and itself being provided with a relatively small scanning aperture, a sec-
